PIVOTAL KNIFE-EDGE ELECTRICAL CONTACT AND A METHOD OF MANUFACTURE THEREOF

Bryce A. Wheeler, Los Angeles, Calif., assignor to Hughes Aircraft Company, Culver City, Calif., a corporation of Delaware

Application May 29, 1957, Serial No. 662,538

6 Claims. (Cl. 339—8)

This invention relates to electrical contact devices and particularly to pivotal electrical contact devices and their method of manufacture.

Rotary electrical contact devices comprised of slip rings and brushes are well known to the art. Where constant electrical contact is desired under conditions of severe vibration, an increase in the brush pressure will usually provide against arcing caused by the brush being jarred from the slip ring contact surface. If arcing does occur, there is irregular current flow and pitting of the slip ring contact surface.

Although an increase in brush pressure is often a satisfactory method for preventing arcing, this technique cannot satisfactorily be employed in situations involving low torque slip ring shaft rotations. An increase in brush pressure with such devices causes higher friction torques which may seriously interfere with shaft rotations. This problem is particularly acute with gyro take-offs, for example, in which only fractional rotations may be involved but in which the introduction of any material frictional effect operates adversely on the gyro device.

It is therefore an object of the present invention to provide an improved electrical contact device utilizing high brush pressure but having minimum friction torque.

It is another object of this invention to provide an improved electrical contact device, operable with fractional rotations, which is characterized by low friction but high contact pressures.

It is another object of the present invention to provide a method for manufacturing an electrical contact device for fractional rotations and for use under severe vibration conditions.

In accordance with the present invention, these objects may be achieved by providing an electrical contact device having brushes in engagement with a plurality of contact elements disposed along the pivotal axis of a nonconductive base member. The base may enclose a portion of the contact elements and plurality of conductors, each attached to a contact element. The contact elements themselves have a contact surface which is machined to a virtual knife-edge. The knife-edges of the contact elements permit the brushes to be adjusted so as to assert a high pressure on the contact surfaces but with minimum friction torque, because of the small area of contact, acting in reaction to the pivoting of the base member. As the base member is pivoted by a low torque source, therefore, the brushes remain in contact even under vibration conditions.

In accordance with another feature of this invention, a process is provided for forming the virtual knife-edged contact surfaces and the base member. The base member containing the contact elements may be rotated about its pivotal axis while the machining apparatus, placed coincident with the pivotal axis of the base member, machines the contact surfaces to surfaces of extremely small radius. The radius of the contact surfaces may be made to approach zero by this method thereby permitting the contact element surfaces to accommodate

2

extremely high brushes pressures. The resultant pivotal electrical contact device will provide continuous electrical contact under severe vibration conditions which cause arcing and will be particularly useful with slip ring shaft rotations of low torque.

The novel features which are believed to be characteristic of the invention, both as to its organization and method of operation, together with further objects and advantages thereof, will be better understood from the following description considered in connection with the accompanying drawing, in which like reference numerals refer to like parts and in which:

Figs. 1 through 4 illustrate the steps of a process, in accordance with the invention, by which a pivotal electrical contact structure may be provided. Fig. 1 is an isometric view of a first step in accordance with the invention, showing a plurality of conductors attached to a plurality of interconnected contact elements;

Fig. 2 is an isometric view, partly cut away, of structure provided in a later step in accordance with the invention, showing the contact elements and conductors of Fig. 1 positioned in a mold;

Fig. 3 is an isometric view of structure provided in a still later step in accordance with the invention, illustrating the manner in which a nonconductive material is molded about the conductors and a portion of the interconnected contact elements of Fig. 2;

Fig. 4 is an isometric view of a final step in accordance with the invention, illustrating a method for machining the excess material from the interconnected contact elements molded in a nonconductive material as in Fig. 3;

Fig. 5 is an isometric view of a pivotal electric contact structure in accordance with the invention as employed as a gyro pick-off; and

Fig. 6 is a cross-sectional view of the pivotal electric contact structure of Fig. 5, taken along the plane 6—6 of Fig. 5, showing a finished contact surface.

One application of the pivotal electric contact, as shown in Fig. 5, is to provide electrical take-offs for gyros which may operate with low torque shaft rotations. However, to better understand the invention and the way by which high brush contact pressures are utilized to overcome the arcing problem, a method by which the invention may be manufactured is described first.

Referring now to Fig. 1, a multiple fingered interconnected contact strip 10, to be used to form the contact elements, is comprised of a base portion 11 and a plurality of fingered contact elements 12 extending from the base portion 11. The contact elements 12 are made of a conductive material such as silver, brass, or copper, all of which have both good conductive properties and good wearing qualities. Base portion 11, which is later removed to separate the contact elements, provides a convenient means for handling the contact elements during the various manufacturing steps. Near the tips of each contact element is secured a conductor 13 which will provide a means for transmitting current flow to the contact elements. The conductors are secured to the contact elements as by soldering, welding, or brazing.

To form a body to align and support the contact elements 12 and to protect the conductors 13, a nonconductive material such as a resinous plastic or ceramic is disposed about the conductors 13 and portions of the contact elements 12. Fig. 2 shows the contact strip 10 placed in a mold 16 with the contact elements 12 and conductors 13 positioned in a die cavity 17. The contact strip is retained and positioned in the mold by a peg 14 inserted through an indexing hole 15 in the contact strip. The free ends of the conductors 13 are inserted into a shaft 18, which also extends into the die cavity 17. The

shaft 18 will form a part of the finished pivotal electrical contact as will become more apparent.

After the contact strip 10 and shaft 18 are properly retained in the mold 16, a nonconductive material is introduced into the die cavity 17 and the hollow of shaft 18 to form a base member 19, shown in Fig. 3. The base member 19 is comprised of grooves 22, lands 21, and a shoulder 20, which is joined to the shaft 18. The lands 21 serve to center the brushes while the grooves 22 provide unobstructed access for the brushes to the contact element surfaces, and also protect conductor 13, shown in Fig. 6, against damage during the subsequent machining step. Since the contact elements 12 are now embedded in and supported by base member 19, the contact strip 10 including portion 11 is removed as by sawing, cutting, or machining along the dotted line 39 shown in Fig. 3.

To form the virtual knife-edged contact surface on the contact element, the shaft 18 is now supported in a collet 24, as shown in Fig. 4. A gang of circular saws 25, 26, having individual saws 26 spaced on a shaft 27 corresponding with the spacing of contact elements 12, is positioned substantially coincident with the pivotal axis line 23 of the base member 19 and in contact with the exposed surfaces of contact elements 12. By rotating collet 24, the base member structure 19 is moved through an angle about the axis line 23, thereby permitting the saws 25 to machine a small arcuate surface on the exposed portions of element 12. As an alternative method, the machining apparatus may be moved about the pivotal axis of the base member 19 while retaining the base member 19 in a fixed position. As shown in Fig. 6, the size of the angle through which the base member 19 is moved about its pivotal axis 23 depends upon the apex angle 28 formed by the surfaces of the grooves 22. With an apex angle of 120 degrees, the base member 19 would be required to be moved through an angle of 60 degrees about its pivotal axis. The radius of the arcuate contact surface 29 machined on the contact element 12 may be made to approach zero. Radii of .001 of an inch have been machined which permit brush pressures up to approximately 40 times greater than those used in other electrical contact devices without any appreciable increase in friction torque.

Fig. 5 shows the finished electrical contact installed for use as a gyro take-off assembly. The assembly is comprised of three brushes 32 extending into a brush shaft 31. Encased within shaft 31 are three conductors 33, each of which is secured to a brush and serves to transmit the electrical current picked up from the contact surfaces 12 by the brushes. The brush shaft 31 containing conductors 33 is inserted through a frame block 35 into a frame member 30 which provides support for the brush shaft. A bolt 34 is used to engage the shaft and to bias the brushes 32 into engagement with the arcuate contact surfaces of contact elements 12.

The shaft 18 of the base member 19 is inserted through a caging arm 36 and is rotatably mounted in the bearing 37 in the frame member 30. The extension of shaft 18 is interconnected with a gyro shaft (not shown). As base member 19 pivots about its axis 23 in response to gyro shaft movements, therefore, the electrical current, carried by the conductors encased in the base member 19, is transmitted to the contact element 12 where it is picked up by the brushes 32. For severe vibration conditions, the brushes may be adjusted to exert considerable pressure on the contact element so as to resist being jarred from the contact surfaces.

It is seen that there has been disclosed a pivotal electrical contact device for use in connection with contact brushes, and its method of manufacture. The device and method disclosed provide a plurality of electrical contact elements having contact surfaces of extremely small radius which will accommodate high contact brush pressures. Because the contact surfaces are a virtual knife-

edge, the high brush pressures cause no appreciable increase in friction torques to interfere with the pivoting action of a low shaft torque contact device. The high brush pressures are utilized to maintain constant electrical contact during operation under severe vibration condition and eliminate arcing caused by the brushes being jarred from the contact surface.

What is claimed is:

1. A pivotal electrical contact structure adapted for use in connection with contact brushes comprised of: a conductor, a contact element secured to said conductor, a nonconductive pivotal base member disposed about said conductor and a portion of said contact element, said contact element having an arcuate contact surface and having a point thereon coincident with a pivotal axis of said base member, whereby a point contact is maintained between said contact elements and the brushes.

2. A pivotal electrical contact structure adapted for use in connection with contact brushes, said structure comprising: a conductor, a contact element secured to said conductor, a nonconductive pivotal base member disposed about portions of said conductor and said contact element, said base member having substantially the configuration of a sector of a right cylinder with an apex angle of less than 180 degrees, said contact element having an arcuate contact surface and having a point thereon coincident with a pivotal axis of said base member, whereby a point contact is maintained between said contact element and the brushes.

3. A pivotal electrical contact structure adapted for use in connection with contact brushes, said structure comprised of: three conductors, three contact elements, each secured to a different one of said conductors, an elongated nonconductive base member having alternate grooves and lands spaced substantially equal along the longitudinal length thereof and perpendicular to a pivotal axis of said base member, said base member having substantially the configuration of a sector of a right cylinder with an apex angle at said pivotal axis of less than 120 degrees and said base member being disposed about said conductors and portions of said contact elements, said contact elements being equally spaced along the length of said base member in said grooves of said base member and having an exposed brush contact surface at said pivotal axis of said base member, said brush contact surface having an arcuate configuration and having a point thereon at a distance less than .003 of an inch from said pivotal axis of said base member, whereby a virtual knife-edge contact is maintained between said contact elements and the brushes during pivoting of said pivotal electrical contact structure about said pivotal axis and through said apex angle of said base member.

4. A pivotal electrical contact assembly comprising: a first conductor, a contact element secured to said first conductor, a nonconductive base member pivotable about a longitudinal axis and disposed about said first conductor and a portion of said contact element, said contact element having an arcuate contact surface and having a point thereon coincident with the pivotal axis of said base member, a brush positioned substantially perpendicular to the longitudinal axis of said base member and in operative relation to the arcuate surface of said contact element, whereby continuous electrical contact is maintained between said brush and said arcuate contact surface during pivoting of said base member about its pivotal axis.

5. A pivotal electrical contact assembly comprising: a nonconductive shaft, three filamentous brushes attached perpendicular to and along the longitudinal length thereof, a first group of three conductors secured to said brushes and encased in said shaft, a second group of three conductors, three contact elements secured to said second group of conductors, an elongated nonconductive base member having alternate grooves and lands spaced substantially equal along the longitudinal length thereof and perpendicular to a pivotal axis of said base member,

said base member having substantially the configuration of a sector of a right cylinder with an apex angle at said pivotal axis of less than 120 degrees, said grooves of said base member being disposed about said conductors and portions of said contact elements and said lands being disposed about said conductors and spaced intermediate said contact elements, said contact elements having an exposed brush contact surface adapted to engage said brushes at said pivotal axis of said base member, said brush contact surface having an arcuate configuration and having a point thereon at a distance less than .003 of an inch from said pivotal axis of said base member, whereby a virtual knife-edge contact is maintained between said contact elements and said brushes during pivoting of said base member about its pivotal axis and through said apex angle of said base member.

6. A pivotal electrical contact assembly comprising: a frame member, an elongated nonconductive base member pivotally mounted on said first frame member, said base member having alternate grooves and lands spaced substantially equal along the longitudinal length thereof and normal to a pivotal axis of said base member, said grooves forming an apex angle at said pivotal axis of less than 180 degrees, a plurality of contact elements individually disposed along said pivotal axis of said base

10

15
